UNITED STATES PATENT OFFICE.

LEE CHAMBERLAIN, OF LOS ANGELES, CALIFORNIA, ASSIGNOR TO CHAMBERLAIN CO.,
INC., A CORPORATION OF CALIFORNIA.

MUD-LADEN FLUID FOR OIL AND GAS WELLS.

No Drawing.

Application filed August 2, 1926. Serial No. 126,747.

My invention relates to oil, gas and water wells, and it has for a purpose the provision of a mud-laden fluid and a method of producing the same by which the flow of gas, 5 oil and water under pressure from a well can be controlled and the sealing up of the interstices in the sides of the well effected.

It is also a purpose of my invention to provide a mud-laden fluid which has a higher specific gravity than similar fluids heretofore proposed so as to render it more effective in controlling or holding down heavy pressures of oil, gas or water. Relatively speaking, the space in a well casing capable 15 of receiving a mud-laden fluid is limited so that only a small portion of the fluid is really active to hold down heavy pressures. I provide a fluid in which its specific gravity is beyond that of fluids such as those containing iron oxide so that its weight for a given length of casing is greater and hence the fluid is more effective in preventing the "blowing" off of a well.

A further purpose of my invention is the 25 provision of a mud-laden fluid which, while having a much higher specific gravity than other fluids of this character, is of a consistency to permit of its being readily circulated to carry off the cuttings and to allow 30 them to drop or settle in the settling ditch with sufficient rapidity to permit of its reuse indefinitely. Further, the consistency of the fluid is such as to prevent its being "gas cut" and thus overbalanced by the gas pressure, thereby preventing the mud column 35 from being expelled from the well.

With the foregoing and other purposes in

view, my invention consists in the provision of a compound consisting of mud, water and iron filings, iron borings and iron scale all 40 ground and mixed in the desired proportion and quantities according to the character of the well being bored. Iron filings, borings and scale are especially suitable because they are substantially pure iron and hence have a 45 high specific gravity. The specific gravity of the fluid is slightly in excess of five. Therefore, by forming a mud containing this material a mud-laden fluid of a specific gravity considerably in excess of other fluids can 50 be readily obtained, while the viscosity can still be kept low enough to permit it to be readily employed in the well without becoming gas cut.

The improved fluid is introduced into the 55 well casing and circulated through the well in the ordinary manner as in the usual practice of forcing water and the ordinary muds through the well, and the fluid will effectively seal up the sides of the well and prevent the blowing out of the oil or gas.

Although I have herein described only one 60 form of mud-laden fluid and one method of producing the fluid, it is to be understood that various changes and modifications may 65 be made from the manner and method described without departing from the spirit of the invention, and the spirit and scope of the appended claim.

I claim:

A mud-laden fluid for oil and gas wells comprising finely ground iron filings, borings and scale.

LEE CHAMBERLAIN.
